DESIGN FOR A DOOR KNOCKER

Ralph Pryne, Los Angeles, Calif.

Application August 10, 1937, Serial No. 70,973

Term of patent 3½ years

To all whom it may concern:

Be it known that I, Ralph Pryne, a citizen of the United States, residing at Los Angeles, in the county of Los Angeles, State of California, have invented a new, original, and ornamental Design for Door Knockers, of which the following is a specification, reference being had to the accompanying drawing, forming part thereof.

Fig. 1 is a front elevational view of a door knocker, showing my new design; and Fig. 2 is a side elevational view thereof.

I claim:

The ornamental design for a door knocker, as shown.

RALPH PRYNE.
